THERMOSTAT

Edward Bletz, Lexington, Ohio, assignor to Westinghouse Electric & Manufacturing Company, East Pittsburgh, Pa., a corporation of Pennsylvania

Application September 5, 1936, Serial No. 99,619

2 Claims. (Cl. 200—139)

This invention relates to thermostats, and more particularly, to thermostats having a bimetallic disc with a snap action.

It is an object of this invention to so arrange the parts of the thermostat that provision may be made for a large arcing space and yet, the device as a whole is compact. This provision is particularly adapted to the control of direct-current circuits, in which the arcing conditions 10 are more severe because the arc is likely to endure longer.

It is a further object of this invention to mount the contact-controlling members on the other face of the main base plate from the bimetallic disc.

It is a further object of this invention to provide means whereby the distance of the bimetallic disc, and simultaneously the distance of the movable contact members from the base plate, may 20 be controlled.

Other objects of the invention and details of the structure will be apparent from the following description and the accompanying drawing, in which:

25 Figure 1 is a sectional view taken through the center of the thermostat when occupying one position;

Fig. 2 is a view in side elevation showing the thermostat in the opposite position;

30 Fig. 3 is a top plan view of the base plate; Fig. 4 is a similar view of the ring which carries the contact buttons;

Fig. 5 is a plan view of the bimetallic disc;

Fig. 6 is a detailed elevation of a securing 35 member for the disc; and

Fig. 7 is a side view of the same member.

In the drawing, the base member 1 is a foundation plate upon which the thermostat is mounted, and is secured in whatever position

40 the thermostat is to be used. It consists of an annular plate having a central opening 2 in which the hub 4 is mounted. The upper surface of the plate 1 is covered with a layer of mica or desired insulation 3, which is provided

45 with a central opening to accommodate the hub 4. The central part of the plate 1 is covered with a supplemental sheet of insulation 5, which is also perforated in the center to accommodate the hub 4.

50 Immediately adjacent the hub 4 is a protective plate 7 which permits the upper end of the hub to be peened over without injuring the insulation. The hub 4 is threaded and supports a threaded member 8 by means of which a bimetallic disc 10 is operatively held in place 55 below the plate 1.

The underside of the plate 1 is covered with insulation 11 and a wire or auxiliary heater 12 is embedded in the insulation 11 to carry a heating current when it is desired to heat the thermostat.

5 The bimetal disc 10 is dish-shaped, as shown clearly in Figs. 1 and 2. Its center is supported by a nut 13, by which the center of the disc 10 is secured between the threaded member 8 and said nut 13 at the bottom of the member which 10 is threaded into the hub 4. The spindle or member 8 is provided with a stem 15 and a head 16 by which it is manipulated.

Upon the upper face of the base plate 1 arcuate conducting members 17 to 21 are secured. 15 These members lie with their ends adjacent each other forming the outline of a circle. Any other closed plane figure would do as well. The end members 17 and 21 of the outline formed by the conducting members are connected to leads 20 24 which extend to the external circuit which is provided with direct current by any suitable means. The members 17 to 21 include a member 18, which is in two parts connected by a bridging portion 25 where the member 18 is laterally 25 deformed to accommodate the passage of a fastening member 27. A hole 28 in the plate 1 accommodates the member 27.

The member 27 is best shown in Figs. 6 and 7. 30 It consists of a cylindrical rod, the upper portion of which is threaded and the lower portion 29 of which has a rectangular cross section, as best seen by comparing Fig. 6 with Fig. 7. The rectangular end 29 of the lower portion of the rod 27 extends through an opening 30 in the 35 bimetallic disc 10. The opening 30 is oval, its long dimension being radial of the disc. When the rod 27 is in such position that the long dimension of its head 29 is in line with the radius of the disc, it is readily passed through the 40 opening 30. When the rod is so turned that its head is in a position at right angles to this, it cannot be withdrawn from the disc. There are openings in the insulation, and in the foundation plate 1 through which the rods 27 are passed, 45 and at their upper end they are threaded into a ring 31 and secured in place by lock nuts 32.

The ring 31 is thus constrained to move with the disc 10 when the disc 10 changes its configuration. The ring 31 carries contact buttons 50 which serve to bridge the gaps between portions 17 to 21. The contact buttons are shown in Fig. 1 at 35, in their circuit-closing position, and are shown in Fig. 2 in their circuit opening position. As best seen at the left of Fig. 1, where 55

one of these buttons is shown in section, it comprises a button proper 36 which is fastened in place by a rivet 37. The button is countersunk so that it can readily tip. The rivet 37 has on 5 the lower side of the ring 31 a convex washer 38 by which the tilting movement of the button 36 can be accommodated. The convex washer 38 is separated from the ring 31 by a washer of mica or other insulation 39, and a second washer 10 of insulation at the upper side of the ring completely insulates the button from the ring. The rivet 37 passes through the center of the insulating washers and the hole in the ring 31 which accommodates it is so large that the rivet does 15 not contact the ring.

Upon the underside of the base plate 1 three stops 40 for limiting the upward snap movement of disc 10 are secured by means of stems 41, which pass through the plate 1 but do not go 20 through the insulation 2. Such a stem is shown at 41 at the left of Fig. 1. The stops 40 and their securing stems are indicated at 41 in Fig. 3, but the rods 27 are not shown in this figure. The holes which accommodate the rods 27 are 25 shown at 28.

In the operation of the device, considering the parts in the position illustrated in Fig. 1, the bridging members or buttons 35 bridge the gaps between the several contact pieces 17 to 21. Beginning at the contact block 17 and proceeding clockwise in Fig. 3 around the outline of a circle, there is a gap at a stop 41, then the long block 18 passes the pin 27 (represented by the hole 28) and a second gap occurs at the next stop 41, after 35 which the block 19 occurs which is connected to the block 20 by the wire 12. This wire affords a bridge around the gap where the second pin 27 occurs. The block 20 is separated from the block 21 by another gap in which a stop 41 occurs.

The blocks 17 and 21 afford terminals to which 40 the leads 24 are connected. The direct-current circuit, which includes the leads 24, sends a current from the block 17 through the several bridging contacts and block 21 and thence into the 45 circuit including the leads 24. A gap containing a pin 27 lies between blocks 21 and 17 but this is never bridged.

When the device becomes hot, either by the current through the wire 12 heating it or by the 50 surroundings being hot or both, the disc 10 because of the unequal expansion of its two layers, reaches a configuration of unstable equilibrium, and then snaps abruptly to the position shown in Fig. 2. In this movement the rods 27 are pushed upward and in consequence, the ring 31 is elevated. This separates the buttons 35 from the conductive members 17 to 21 and breaks the current through the circuit 18.

If this current is heavy, the breaking may be 60 accompanied by an arc across each of the several gaps. When this occurs, it is desirable that the arc shall not act upon the bimetallic disc 10, either to heat it or to increase corrosion. This is prevented by the circumstance that the disc 10 is on the other side of the foundation plate 1, and because of the several sheets of insulation 65 segregating the region where the arcs form. The ring 31 and consequently, the button 35, are moved so far from the conductive members 17 to 21 that the arcs are extinguished.

When the parts cool, the disc 10 is strained in 70 the opposite direction and after passing a certain critical temperature, it snaps back to the position illustrated in Fig. 1. This movement brings the ring 31 abruptly downward toward 75 the foundation plate 1.

In the position shown in Fig. 1, the several buttons 35 bridge the corresponding gaps in the outline 17 to 21, and in doing so each button tilts about its pivot as much as may be necessary to accommodate itself to the out-of-level position of the ring 31 or to the lack of uniformity in the thicknesses of the parts 17 to 21.

When the device is in the cooled position, rotation of the head 16 may cause the threaded member 8 to rise in the hub 4. This will draw 10 the central part of the disc 10 upward but the rods 27, being secured in the holes 30, prevent the peripheral part of the disc from rising. The curvature of the disc may thereby be increased. If the head 16 is rotated in the opposite direction, 15 the curvature may be lessened because of similar considerations. By this adjustment, the critical operating temperature of the disc may be predetermined.

When the disc snaps to the open position, it 20 does not move an indefinite distance, but its upper movement is limited by the stops 40. The points in the disc which abut the stops 40 are near, but not at the periphery. When the disc is in the position represented by Fig. 2, adjustment of the head 16 may cause the disc to change 25 its configuration because its periphery is held by the stops 40 from further upward movement. If the head 16 is turned in the direction to cause the disc to descend, its configuration need not 30 thereby be changed because the rods 27 and the ring 31 can descend with it. No effect, except an increased tendency to snap, can occur from rotation of the head 16 when the parts are in the Fig. 2 position, but in the Fig. 1 position, the pressure between the buttons 35 and the contact members 17 to 21 can be regulated by turning the head 16.

Variations in the details of construction may 35 be made within the skill of those skilled in the art. The specific illustration and description of one form of the device is not to be considered a limitation. The only intentional limitations are those expressly stated in the claims or necessarily required by the prior art.

I claim as my invention:

1. In a thermostat, a base plate, a thermally responsive disc adjustably mounted on the base plate at one face thereof, a carrier on the other side of said base plate from said disc, means secured to said disc near the periphery thereof and mechanically securing it to the carrier, conductive members separated by gaps and insulated from, but secured to, the base plate on the face toward the carrier and forming an outline having adjacent ends, leads united to the end ones of said conductive members, bridging pieces, one for each of the gaps, except the gap separating said end conductive members, said bridging pieces being mounted on, but insulated from, the carrier, the mounting of said disc including means for moving the center thereof to vary its distance from the base plate whereby with the bridging pieces in contact with the conductive members, adjustment of the mounting of the disc will vary the pressure of the bridging members against the conductive members and also the configuration of the disc.

2. In a thermostat, a base plate, a thermally responsive disc adjustably mounted on the base plate at one face thereof, a carrier on the other side of said base plate from said disc, means secured to said disc near the periphery thereof and mechanically securing it to the carrier, conductive members separated by gaps and insulated from but secured to the base plate on the face 70

toward the carrier, leads united to the end ones of said conductive members, bridging pieces, one for each of the gaps, except the gap separating said end conductive members, said bridging pieces being mounted on, but insulated from, the carrier, the mounting including means for per-

mitting a tilting movement of the bridging pieces relative to the carrier, whereby the bridging pieces will always contact the conductive members flatly.
